John Partridge of Zanesville, Ohio
Letters Patent

The Schedule referred to in these Letters, Patent and matter first
of the same containing a description in the words of the said John
Partridge himself of his improvement in the manufacture of
wooden Ware without Staves.

To all to whom these presents shall come, Be it known
that I John Partridge of Zanesville, in the County of Muskingum,
and State of Ohio, have invented a new and useful im-
provement in the manufacture of wooden ware without staves,
such as Tubz, Buckets, Hooletz, Chumz, Regs, Barrels, &c,
and that the following is a full and exact description of the con-
struction and operation of the said machine as invented, or
improved by me. A common tub of heavy timber built
in the most substantial manner (requiring Steam or Water power
&c) proportioned as represented by the Drawing. The block
in its rough state, first necessarily贯穿 through the center
with a hole of suitable size in order to be glued on the
mandrel, and turned in the usual way, with the small
end near the guide (7) the gauge gauge is then placed on
the rest (3) and the guide (7) regulating the tool by the guide
to the bore of the block, the operation of cutting the rims of
the ware is then commenced by sliding the tool up to the block,
the entering of the tool is regulated by the end of the stock,
near the gauge forming a sage, which can be altered at pleasure
to suit the thickness wanted for the rims, as represented
in figure (8). When this operation is performed, the cutting of
the cross (proper for the bottom) is next done, the small end of the
stock being near the rest (3) by inserting a tool made for that
purpose as shown in the drawing fig 9. It is now finished with
the exception of cutting through with a chisel at the distance
from the end, when the nose was cut, to suit the size of the
ware.

Apr. 16, 1831

The rim is now completed, and steps off in a state ready for fitting in the bottom. The gage gauge in its progress, cutting each side perfectly smooth, rendering any other operation unnecessary. Proceeding in the same manner the rest in sizes is cut, and so on, till the whole block is finished forming a nest wave of the largest size down to the smallest. By commencing at the small end of the block and dispensing with a screw head, every piece of ware unfinished steps off saving the time of unscrewing and taking the block out of the lathe, for every single rim that is turned. By commencing at the small end, the timber at the large end is saved for another rim, as the block is sufficiently long to make four two foot pieces of the smaller wave, a considerable saving of labor and timber. The gage gauge is formed of a piece of iron three eighths of an inch thick, one and a half inch wide, and two feet in length, narrowing toward the end, the gauge is placed both in width and thickness, the gauge forming a little more than half a circle as figure 8 and placed nearly perpendicular as represented by fig. 1. The upper corner slightly rounded off. The iron plate being fastened to the centre leaving a space on each side of the plate in the hollow of the gauge as fig 8. Three holes made at the other end to receive the bolts of the block or handle in order to be secured fast. The gage is secured on the upper edge of the plate by a piece secured on near the bolt holes and connected with the gage by a hinge. The end near the gage is fastened down with a screw, the gage gauge is secured in the block or handle by three bolts as shown in the drawing. The crooked or tool for cutting the crop (groove for the bottom) is similar to a spur rabbit plane with a gage to regulate the distance from the edge of the rim as represented by figure 9. a left handed gage gauge, and a left handed crooked, are also used, being necessary in turning the rims of charms, keys, barrels, &c.

I claim as my invention the manner of fixing the block in the lathe, the application of the gage gauge and crooked

at each end of the rim, the sawing operation of labor, and sawing of timber. The gauge gauge and croise (tool for cutting the groove) to receive the bottom. (Fayetteville 28. Oct 1830.
